UNITED STATES PATENT OFFICE

171,531

COSMETIC AND MEDICINE CONTAINER

Samuel Cramer, West Hartford, Conn.

Application January 26, 1953, Serial No. 23,299

Term of patent 14 years

(Cl. D58—9)

To all whom it may concern:

Be it known that I, Samuel Cramer, a citizen of the United States of America, residing at West Hartford, Connecticut, have invented a new, original, and ornamental Design for a Cosmetic and Medicine Container, of which the following is a specification, reference being made to the accompanying drawing, forming a part hereof.

The characteristic feature of my design resides in the cap portion.

I claim:

The ornamental design for a cosmetic and medicine container, as shown and described.

SAMUEL CRAMER.
